UNITED STATES PATENT OFFICE.

EBER SMITH, OF NELSON, ENGLAND, ASSIGNOR TO THE FIRM OF PICKLES BROTHERS, LIMITED, OF BRIERFIELD, NEAR BURNLEY, ENGLAND.

CHANGE-BOX MECHANISM FOR LOOMS.

1,266,171.

Specification of Letters Patent. Patented May 14, 1918.

Application filed January 25, 1915. Serial No. 4,146.

To all whom it may concern:

Be it known that I, EBER SMITH, a subject of the King of Great Britain, and resident of 168 Leeds road, Nelson, in the county 5 of Lancaster, England, have invented a certain new and useful Improvement in Change-Box Mechanism for Looms, of which the following description, having reference to the accompanying sheets of drawings, is 10 a specification.

This invention relates to pattern surface mechanism for controlling the movements of shuttle boxes of a type wherein the pattern surface, usually consisting of lags and 15 pegs, is contacted with by an indicating lever which moves step by step lengthwise over each of said peg lags commencing at one end thereof and finishing at the other, and the present invention has more especial 20 reference to that particular arrangement of this type of mechanism wherein the step by step action of the indicating lever is carried out in both directions, that is to say, each peg in the peg lag being contacted with 25 from one end of the lag to the other in one direction and the succeeding lag theron commencing its indicating actions from this latter end and back to the former, and the object of the present invention is the production of devices and the arrangement of 30 the mechanism for transmitting motion to the pattern cylinder carrying the peg lags, so that an additional pattern surface might be made use of for controlling the movements of the former pattern surface so that 35 repetitions of same in any desired order may be carried into effect and the movements of other parts of the loom also controlled.

40 In the accompanying sheets of drawings which are illustrative of my invention:—

Figure 1 is a front elevation of mechanism made in accordance with my invention, the same being illustrated as mounted upon 45 the upper end of the framework of the loom.

Fig. 2 is an end elevation as seen in the direction of the arrow α on Fig. 1.

Fig. 3 is an end elevation as seen in the opposite direction to that indicated by the 50 arrow α .

Fig. 4 is a sectional end elevation of the machine as seen in the same direction as Fig. 2.

Fig. 5 is an end elevation drawn to a re-

duced scale and illustrates my improved 55 mechanism mounted upon the upper part of a loom so that the connections from said mechanism to the levers which control the shuttle box may be more clearly understood.

Fig. 6 is a sectional end elevation seen in 60 the same direction as Fig. 3, but illustrates parts that are behind those shown by said Fig. 3.

Fig. 7 is a similar view to Fig. 4, but 65 illustrates certain of the parts in different relative positions.

Fig. 8 is a plan of a portion of the parts shown by Fig. 7.

Figs. 9, 10, 11 and 12 are drawings in detail of parts hereinafter described. 70

Similar letters and figures of reference indicate similar parts throughout the several views.

A indicates the end frame of the loom (see Fig. 5) B the top rail or upper framework of said loom and C, C¹ the end frames upon which my operating parts are mounted. 75

The type of machine to which my invention relates is that wherein a rotary pattern barrel 2 (Figs. 1, 4 and 7) is mounted upon 80 fixed bearings carried by the end frames C, C¹ so that intermittent rotary motion may be transmitted to said barrel 2 by one or other of the operating catches hereinafter described.

In connection with this intermittently rotary barrel 2 a bracket 3 having an internal thread formed through it, is mounted so that the screw 4 will take therein in order that as said screw 4 is rotated by either of the pawls 5 or 5^a said bracket 3 is 85 made to travel over or lengthwise said screw 4. The pawls 5, 5^a are pivoted upon the bearings at 5^b while the screw 4 is mounted to revolve in openings made through the outer ends of the lever arms 6 and 6^a. These 90 lever arms are fixed upon a shaft 7 which is mounted to oscillate loosely in openings or bearings made at the upper ends of the end frames C and C¹; and oscillatory motion is transmitted to said arms 6^a and 6 in a vertical direction by the extending arm 95 6^b of the lever 6^a having a stud or pin 6^c fixed upon it so that the slotted rod 8 may take over same. This slotted rod 8 is pivoted upon the lever arm 9, which is fixed to 100 the shaft 10, and said shaft 10 extends across the machine being supported by the two end frames C and C¹. Upon the other

end of the shaft 10 is fixed a lever 11 (see Fig. 2) upon which is fixed a pin or stud 12. Over this pin or stud 12 a bifurcated sliding rod 12^a is made to take, so that 5 upon said rod 12^a a hook or pawl 13 may be pivoted at 12^b and held by a spring 13^a so as to be in contact with said stud 12. The extension 14 of the rod 12^a reaches down to one or other of the motor shafts of the loom 10 preferably the low shaft so that an eccentric mounted thereon will cause said rod 14 to move or reciprocate vertically. The vertical motions of the rod 14 are such that the hook 13 in its descent will engage with the 15 stud 12 and pull down the lever 11, causing the shaft 10 to oscillate and by the lever 9 and slotted rod 8 thus pull down the extending arm 6^b and cause the arms 6 and 6^a to raise the screw 4. The descent of the 20 outer ends of the lever arms 6 and 6^a is effected by the retracting spring 15 (see Figs. 3 and 5) thus the screw is positively raised but is permitted under the recoil of the spring 15 to descend until arrested in its 25 descent (a) by the upper surface of a peg lag 2^a on the barrel 2 as shown by Figs. 1 and 4) (b) by the short peg 16^a or (c) by the long peg 16 (see Fig. 1). These pegs 16, 16^a in the peg lags 2^a are of two lengths the longer one 30 16 being thus enabled to arrest the motion or descent of the bracket 3 and therefore the lever arms carrying same in a higher position, while the shorter peg 16^a arrests it in the next lower position and in the absence 35 of such pegs then the bracket 3 descends until it rests upon the peg lag 2^a of the barrel 2. Thus I have three positions of the bracket 3, and consequently three positions of the arm 6^b of the lever 6^a and it is from 40 this arm 6^b that these three positions are made to control (through the connecting rod 17 (Figs. 3 and 5) and lever 17^a, which is fixed upon the shaft 18) the vertical fingers 19, 19^a also fixed upon said shaft 18. 45 These fingers 19, 19^a are of the formation shown by Figs. 9, 10, 11 and 12, and are so situated upon the shaft 18 that as same oscillates they are carried so that their upper outer ends follow a curved path beneath 50 pins 20 and 20^a carried by vertical connecting rods 21, 21^a respectively. These rods 21, 21^a are coupled to the shuttle box controlling levers 22, 22^a of ordinary construction so that should said pins 20 or 20^a be retained 55 in their highest position then their corresponding levers 22 and 22^a will be retained from putting the shuttle box operating mechanism into action in manner well known. The levers 22 and 22^a are continuously reciprocated from the usual fork device 23 (see Fig. 5) as is well understood, and as fully explained in the specification of U. S. Patent No. 526,036 granted to Hill and Smith.

60 Provided the shaft 18 is in position so

that the pin 20 may descend into the opening *w* in the finger 19 (as in the case shown by Fig. 9) then the lever 22 is permitted to put the shuttle box operating mechanism into action, whereas at such time the finger 19^a 70 will have retained the pin 20^a in its raised position. Should the pin 20^a descend by reason of its finger 19^a being moved clear of it as shown by Fig. 10, then the other lever 22^a will put the shuttle box operating mechanism into action; whereas should the fingers 19 and 19^a be in positions as shown by Fig. 11 to arrest both of the pins 20 and 20^a then the shuttle box mechanism remains inoperative. As shown by the drawings, when 80 the finger 19 is in the position shown by Fig. 9 the finger 19^a will have its upper end beneath the pin 20^a, while when the finger 19^a is in the position shown by Fig. 10 then one part of the outer end of finger 19 will 85 be beneath the pin 20, whereas when the fingers are in the positions shown by Fig. 11 then both of them lie beneath and prevent the descent of the two pins 20 and 20^a. As the lever arms 6 and 6^a are raised the 90 peg wheel 24 on the end of the screw 4 is made to engage with one or other of the pawls or catches 5 or 5^a, the pawl 5^a being shown in position by Fig. 2, so that as same continues to ascend the screw 4 is rotated 95 through the space of one fourth of a revolution according to the arrangement of the peg wheel 24 illustrated, thus the bracket 3 at such intermittent rotations of the screw 4 is carried step by step from one side of the 100 machine to the other so as to engage with any peg 16 or 16^a that may be fixed in the peg lags 2^a. On the bracket 3 reaching the side of the machine (say the left hand side, of Fig. 1) a projecting part 25^a extending 105 laterally from the lever 25 (pivoted upon said bracket 3 at *x*) will be brought so that it will come into contact with and be arrested in its descent by the upper end of a lever 26, thus the descent of the screw 4 and 110 bracket 3 will cause said lever 25 to oscillate about its pivot *x* so that its rear or extending end 25^b will depress the cross bar 27 and so oscillate the arms 27^a (one being on each side of the machine) upon which said bar is 115 fixed in order that the pivotal pin 27^b (which extends through the end frame of the machine and has fixed upon it the retaining ratchet 28) will cause said ratchet to move clear of the stud 28^a fixed in the lever arm 120 29^a of the lever 29, hence at such time the other end of said lever 29 will descend so that one or other of the pawls 30 or 30^a will engage with the peg wheel 31 fixed upon the shaft of the cylinder 2. This engagement of the pawl 30 or 30^a with the peg wheel 31 has the effect of transmitting intermittent motion to the cylinder 2 on the next 125 ascent of the lever 29 and this lever at such time is caused to ascend by means of the 130

overhanging stud 29^b coming in contact with it, when the connecting rod 8, to which said stud 29^b is fixed, descends.

The holding ratchet 28 is retracted or held 5 normally in engagement with the stud 28^a by means of the spring 28^b.

On the bracket 3 reaching the opposite or right hand side of the machine, the projection 25^b on the lever 25 engages with the 10 upper end of another lever 26^a (Fig. 1) and so effects the engagement of the ratchet 30 or 30^a with the peg wheel 31 in the same manner as does the lever 26 above described.

The levers 26 and 26^a as above described 15 are for effecting the engagement of the operating pawls 30 and 30^a so that the cylinder 2 is put into operation and during the ordinary movements of the machine the lever 26 is actuated by the cam 26^w acting against a 20 spring 26^x fixed to said lever 26 (see Figs. 4 and 7). On the cylinder 2 being rotated one stage farther or from the position shown by Figs. 4 and 7, then the point of the cam is taken away and the spring 26^x retracts 25 the lever 26 and moves it out of the path of the lever 25^a. In this latter position it (said cam 26^w) will remain and when the bracket 3 has moved to the opposite side of the machine so that the lever 25 is brought for 30 its projection 25^b to descend into contact with the upper end of the lever 26^a which will have moved into and which at such time will be fixed or held in position for effecting a reversal as did the lever 26 on 35 the former occasion, since the lever 26^a is fixed upon the same shaft 26^b as is the lever 26.

As the cylinder 2 is rotated the cam 5^e (which is fixed upon the cylinder shaft 2^e) 40 is rotated with it and by the actions of this cam 5^e when same is arrested in one position one ratchet as 5^a is in engagement with the peg wheel 24, as is shown by Fig. 2, while on the next intermittent movement of the 45 cylinder 2 it will bring the ratchet 5^a out of engagement with the peg wheel 24, and simultaneously permit the ratchet 5 to fall into gear therewith. When the cylinder 2 is being rotated the cam 5^e being simultaneously 50 rotated causes both of the catches 5 and 5^a to move clear of the peg wheel 24 so that at such time no rotary motion is transmitted to the screw 4. The retracting spring 5^d permits the cam 5^e to operate the 55 ratchets 5 and 5^a as described since said spring keeps them normally in contact therewith.

In the mechanism hereinbefore described, 60 the employment of two pawls 30 and 30^a and the employment of the vertical levers 26 and 26^a forms a portion or part of my present invention, whereas the other parts and the functions they perform, are already well known. To the mechanism hereinbefore described I further add my improved parts

which control the movements of the cylinder 2 and other parts in such manner as to attain the object of my invention.

Upon the outer end of the shaft 2^e upon which the cylinder 2 is fixed (see the extreme left of Fig. 1) I mount to rotate loosely an additional cylinder 32 over which chains of cards 32^a may be made to take in order that projections *s* fixed upon said cards may be brought beneath a feeler lever 33. 70 This feeler lever 33 is fixed upon a short shaft or spindle 34, and this spindle 34 is carried by a bracket 35 supported by the end frame C^x.

On the other end of this spindle is fixed 80 a lever 36 carrying at its lower end a connecting rod 37, the other end of which is connected to an oscillating plate 38, this plate 38 being pivoted at 38^a upon a support fixed on the end frame C^x, thus when there 85 is no peg *s* beneath the lever 33 (which position is shown by Fig. 3) the oscillating plate 38 is in the position so that the lever 39 pivoted at 39^a upon said plate 38 will permit the ratchet 30 to engage with the peg 90 wheel 31, while when a peg *s* raises the lever 33 then the plate 38 is oscillated in the opposite direction or to the opposite side (as shown by Fig. 6) so that the guiding lever 40 pivoted at 40^a also to the plate 38 will 95 permit the ratchet 30^a to engage with the peg wheel 31, and will at the same time force the ratchet 30 out of engagement with said peg wheel. In this manner the pegs *s* on the 100 cards 32^a determine the direction in which the shaft 2^e and consequently the pattern barrel 2 shall rotate. The guiding levers 39 and 40 are held against the stop pieces 38^b and 38^c formed on the plate 38 by means of the spring 41.

Intermittent rotary motion is transmitted 105 to the pattern barrel 32 by means of the pawl 42, which is pivotally mounted upon the lever arm 29 and to prevent said pawl 42 from rotating said cylinder 32 by engaging at all times with the peg wheel 43 which is fixed upon the pattern barrel 32, a finger 44 fixed upon the shaft 44^a is made to retain said pawl 42 out of engagement with the peg wheel 43 at all times until a peg or extension 110 45 carried by a peg lag 2^a (see Fig. 1) comes into the path of and operates a lever 46 which is fixed upon the other end of the shaft 44^a; at such time, on the ascent of the lever 29 to carry the pawl 42 beyond the lever 44, when the peg 45 operates the lever 46, 115 said arm or lever 44 moves beyond the path of the pin 42^a carried by the pawl 42, hence said pawl 42 descends between the lever arm 44 and the peg wheel 43, and thus it is permitted on its next ascent to transmit movement to the cylinder 32.

At the time that the bracket 3 is on the 120 left hand side of the machine and in position so that the projection 25^a on the lever 25

might engage with the vertical lever 26, should a peg *s* at that time be in position to operate the lever 33 and rotate the spindle 34 then the lever 47 will be moved forward 5 and will force the lever 26 beyond the position where it can arrest the descent of the projection 25^a (as shown in broken lines by Fig. 7) hence at such time there is no motion transmitted to the pattern barrel 2 before 10 cause its operating pawl will not have descended at that time on account of the retaining pawl 28 not having been pulled out of engagement. When these actions occur the bracket 3 may engage with the last hole 15 for pegs in the peg lags 2^a on this left hand side of the machine for the purpose of enabling the indications of the pattern surface to re-commence at the leading end and not to be inversely repeated.

20 In operation, as the bracket or detector 3 moves freely over the screw 4, say from left to right, Fig. 1, it will eventually engage a peg 45, carried by the peg lags 2^a, and actuate lever 46, so that the cylinder 32 may be 25 put in motion. Then should a peg *s* on the pattern surface 32^a, move the parts heretofore described, the rotary motions of the pattern cylinder will be first arrested and then reversed as to direction. It will be understood 30 that the bracket or detector 3 may be arranged to contact with the whole series of pegs in the pattern surface carried by cylinder 2, and by bringing into action such pegs as are at the ends of the lags, near lever 35 26, and causing the cylinder at that time to be reversed after the last peg has been contacted with, intermittent rotary motion may be transmitted to the cylinder 2, each time that the lever 29 rises. This action is effected 40 by means of the pawl 30^a being in engagement with the peg wheel 31, during all the time that the lever 33 is in its raised position, and this raised position is maintained so long as a peg remains below said lever 33. To arrest the said motion of the cylinder 2, a peg 45 on the main pattern surface 2^a is arranged to be brought into position to actuate the parts hereinbefore described, in order that the pawl 42 may engage 45 with the peg wheel 43 to move said pattern surface 32^a to take the projections from being beneath the lever 33. This is effected at such times relatively with the motions of the other parts that the cylinder 2 and its operating ratchet 30 again commence their usual motions which will be the commencement of the pattern as carried by the pattern surface.

As hereinbefore stated the step by step 60 action from side to side of the pattern surface of the feeler lever 3 is carried out during the ordinary motion of the cylinder 2, with the exception that on the left hand side of said cylinder 2 one hole at the end of each 65 of the peg lags 2^a on this side of the machine

is not ordinarily contacted with, since it is this hole that is contacted with during the intermittent motions of the cylinder 2 in the opposite direction as hereinbefore described. These series of holes at the ends of the lags 70 enable the controlling effect of the pattern surface to be brought into use so that should the pattern end in the middle of a lag, or at any part between the two ends of a lag, then the next or succeeding lag will commence immediately behind the end of the pattern in the preceding lag so that the reversal of the feeler lever 3 at this time causes same to travel back to the left hand side of the machine and there bring the projection 80 25^a into contact with the devices as hereinbefore explained. This movement of the bracket 3 vertically during the time that the cylinder is intermittently rotated and without leaving such position until the end of 85 the pattern is reached, causes the reversal of the direction of motion of the lever 3 to be effected from its advancing position from the left to the right by the projection 25^b of the lever 25 contacting with the projection 90 60 on the peg lag 2 as is illustrated by Fig. 1.

In connection with my apparatus I make use of that lever which is actuated on the breakage or failure of the weft to operate the 95 rod 50, so that by the lever 51, which is loosely mounted upon its stud 52, it may throw the catch or pawl 13 out of the path in which the stud or pin 12 lies. By this action on the descent of the rod 14 the hook 100 or pawl 13 misses said stud 12 and so fails to operate any part of the mechanism.

Such being the nature and object of my said invention, what I claim is:—

1. Change box mechanism for looms comprising a pattern barrel, a pattern surface carried thereby, a traveling detector member, shuttle box mechanism controlled by said detector member, a supplementary pattern surface controlling said pattern barrel, 105 and means operated by said detector for actuating said supplementary pattern surface.

2. Change box mechanism for looms comprising a pattern barrel, a pattern surface carried thereby, a traveling detector member, shuttle box mechanism controlled by said detector member, pawls for operating said pattern barrel, a supplemental pattern surface, means actuated by said supplemental pattern surface for controlling said 115 pawls, and means operated by said detector for actuating said supplemental pattern surface.

3. In change box mechanism for looms, a pattern barrel, a pattern surface carried by 125 said pattern barrel, a screw, means for rotating the screw, a detector lever movable on said screw and arranged to contact with said pattern surface, vertical levers 26, 26^a, a lever 25 carried by said detector lever and 130

having a bifurcated end for contact with said levers 26 and 26^a, and means whereby said lever 25 may cause said screw-rotating means to impart reverse motion to said 5 screw.

4. Change box mechanism for looms comprising a primary pattern barrel, a pawl for rotating said barrel in one direction, a second pawl for rotating the barrel in the opposite direction, a supplementary pattern 10 surface, a pattern barrel for the supplementary pattern surface, an oscillatory plate, means controlled by the supplementary pattern surface for oscillating said plate, and means actuated by the plate for selectively controlling said pawls.

5. Change box mechanism for looms comprising a primary pattern barrel, pawls for operating the same, pivotally supported levers positioned to engage and move said pawls into and out of operative position, a yieldable connection for said levers, a supplementary pattern barrel, and means controlled by the supplementary pattern barrel 25 for selectively actuating said levers.

6. Change box mechanism for looms comprising a primary pattern barrel, pawls for operating the same, pivotally supported levers positioned to engage and move said pawls into and out of operative relation, an oscillatory plate connected with said levers, a supplementary pattern barrel, and means controlled by said supplementary pattern barrel for oscillating said plate to selectively actuate said levers. 30

7. Change box mechanism for looms comprising a pattern barrel, a pivoted lever provided with pawls for actuating said barrel, a detector, means for causing said detector to travel parallel with said barrel, 40 control levers located at the ends of the pattern barrel and positioned to be engaged by said detector, and means placed in operation by the engagement of the detector and either of said control levers for actuating the pawl 45 lever.

EBER SMITH.
